UNITED STATES PATENT OFFICE.

JOSEPH F. CLAESGENS AND FREDERICK A. GEIGER, OF ROCHESTER, NEW YORK.

FLYING-MACHINE.

1,133,707.

Specification of Letters Patent. Patented Mar. 30, 1915.

Application filed May 9, 1914. Serial No. 837,573.

To all whom it may concern:

Be it known that we, JOSEPH F. CLAESGENS and FREDERICK A. GEIGER, citizens of the United States, residing at Rochester, in 5 the county of Monroe and State of New York, have invented certain new and useful Improvements in Flying-Machines, of which the following is a specification.

The object of this invention is to provide 10 a new and improved flying machine. This and other objects of the invention will be fully illustrated in the drawings, described in the specification and pointed out in the claims at the end thereof.

15 In the accompanying drawings, Figure 1 is a side elevation of the machine. Fig. 2 is a top plan view of the frame work of the machine, the view being taken on the section line 2^x-2^x of Fig. 1. Fig 3 is a top plan 20 view of the machine. Fig. 4 is a section on the line 4^x-4^x of Fig. 3. Fig. 5 is a front elevation of the machine.

In the accompanying drawings, like reference numerals indicate like parts. 25 The flying machine is provided with a ring 1, from which rise four posts or uprights 2, 3, 4 and 5. Near the top of these posts, is fastened the ring 6 and at the top of the post, is fastened the ring 7. Each of 30 these posts passes through and is fastened to these rings 6 and 7. Projecting radially from the ring 6, are the tubular ribs 8 which support on their periphery a tube 9, which makes a complete circle.

35 The canvas cover 10 of the aeroplane, is attached under the plate 6 and under the ribs 8 and to the tube 9. At the center the canvas cover 10 is clamped between the plate 6 and the plate 11. The central portion of the canvas cover within the ring 6 may be cut away to leave an air hole.

From the ring 7 to the rim 9 are stretched 45 the stays 12 above the aeroplane. Below the aeroplane stays 13 are stretched from the rim 9 to the ring 1. The stays 12 and 13 may be continuous if so desired. The stays 12 are uniformly distributed around the whole aeroplane but the stays 13 are omitted where they will interfere with the operation of the propeller at the forward part 50 of the aeroplane and where they are omitted, the tangential stays 14, 15, 16, 17, 18 and 19 are furnished instead, all of these stays 14 to 19 inclusive, being placed below 55 the aeroplane.

Mounted under the ring 1 are the four lugs 20, 21, 22 and 23, each of which lugs has a hole therein that extends horizontally therethrough. Through these holes extend the rods 24 and 25. These rods are mounted 60 to slide in these holes and are clamped therein in any desired adjustment. The rods 24 and 25 are connected into a frame by the cross bars 26 and 27. This frame is capable of sliding as a whole longitudinally under 65 the ring 1 and may be adjusted to and clamped in any desired position in any suitable manner.

Depending from the ring 1 are the brackets 28 and 29 on which are supported the 70 wheels 30 and 31 on which wheels the machine normally rests on the ground and on which wheels the machine rests when it is on the ground. From the cross bar 27 extends downwardly the bracket 32 on which 75 bracket the wheel 33 is mounted, on which the rear end of the frame rests on the ground.

The engine 34 is mounted on the ring 1. 80 The shaft 35 is driven thereby. This shaft extends through the cross bar 26 in which it has a bearing. The shaft 35 carries on its end the propeller 36 which propeller is rotated by the power of the engine and by which propeller, the aeroplane is driven.

Carried on the ring 1 is the seat 37 for 85 the operator of the machine and the steering wheel 38. Connected to the steering wheel 38 is the pulley 39 to which is connected the steering rope 40 which in turn 90 is connected to the pulley 41. This pulley is mounted to swing on the horizontal plane 42 on which it is pivoted. This pulley carries the vertical plane or rudder 43 and as 95 the rope 40 is pulled back and forth by the operation of the steering wheel, the rudder 43 is oscillated. The plane 42 is mounted so that either the forward or rear edge thereof can be depressed. For this purpose, 100 a supporting frame is provided as follows:

Cross bars 44 and 45 are provided from 105 which the stems 46 and 47 depend at the middle thereof. Supported from these stems is the bar 48. The plane 42 is mounted to slide on the stems 46 and 47. The stems 46 and 47 are encircled by helical springs which are placed under the plane 42 and which press the plane upward. Mounted below the bar 48, are the pulleys 49 and 50, over which pass the ropes 51 and 110

52, the rope 51 being fastened to the rear end of the plane 42, and the rope 52 being fastened to the front end of this plane. The rope 51 is connected to the pedal 53 and 5 the rope 52 is connected to the pedal 54 at the front of the machine, these pedals operating when depressed by the operator's foot to draw the rope and draw down either the rear or the front end of the plane 42, 10 compressing the spring on the stem 47 or 46 as the case may be. This operation of the plane as the machine is traveling forward, will cause the machine to go up or down the operation of the rudder 43, causing the 15 machine to go to the right or the left as may be desired.

A gasolene can 56 is suspended under the ring 1.

I have shown the aeroplane as being circular in shape and dished, with the concave opening downward. I do not wish however, to be restricted to this form of aeroplane and while keeping it preferably circular in shape, the curvature longitudinally of the 20 machine may be retained, while the curvature of the aeroplane transversely of the machine, may be eliminated or may be varied from the full curvature used longitudinally of the frame to the straight line that 25 may be substituted therefor, transversely of the frame. It will also be observed that as shown in Fig. 1 the motor and propeller and other heavy parts of the machine will be below and a little forward of the center 30 of the plane while the rudders will be at the rear below or beyond the periphery of the plane. This arrangement places the center of gravity below or approximately below the center of the aeroplane and gives 35 stability to the machine so that it will always 40 right itself.

I claim:

1. In a flying machine, the combination of an aeroplane, an upright frame for supporting said plane, a ring at the bottom of said plane, a plurality of perforated lugs integral with said ring, a horizontal frame having a pair of bars therein passing through the perforations in said lugs and 45 50 making a sliding engagement with said vertical frame.

2. In a flying machine, the combination of an aeroplane, an upright frame for supporting said aeroplane, a horizontal frame for supporting the propeller and rudders of said flying machine, said horizontal frame having a sliding engagement with said vertical frame, a ring mounted on said vertical frame, a motor mounted on said ring for driving said propeller. 55 60

3. In a flying machine, the combination of an aeroplane, a horizontal frame suspended therefrom, a horizontally extending rudder mounted on said frame and being adapted to swing around either its forward 65 or rear edge, a vertically extending rudder pivotally mounted on said horizontally extending rudder and adapted to swing thereon.

4. In a flying machine, the combination 70 of an aeroplane, a frame suspended therefrom, cross bars mounted on said frame, stems extending downwardly from said cross bars, a horizontally extending rudder having perforations therein adapted to engage with said stems, said rudder being thereby mounted to slide on said stems, springs on said stems below the rudder adapted to normally hold the front and back of said rudder at the top of said stems, 75 a driver seat on said frame, means accessible from said driver seat for depressing either the forward or rear edge of said horizontal rudder. 80

5. In a flying machine the combination of 85 a circular aeroplane, an upright frame for supporting said plane and motor, a horizontal frame for supporting the propeller and rudders of said flying machine, said horizontal frame being adjustable relative 90 to said upright frame, the weight of said upright and horizontal frames being disposed so as to put the center of gravity thereof substantially below the center of the circular aeroplane. 95

In testimony whereof we affix our signatures in presence of two witnesses.

JOSEPH F. CLAESGENS.
FREDERICK A. GEIGER.
